UNITED STATES PATENT OFFICE.

REYNOLD JANNEY, OF NEW YORK, N. Y., AND JOHN J. CRAIN, OF WALLINGFORD, CONNECTICUT, ASSIGNORS TO THE WATERBURY TOOL COMPANY, OF NEW BRITAIN, CONNECTICUT, A CORPORATION OF CONNECTICUT.

DRIVING MECHANISM.

1,197,029.

Specification of Letters Patent. Patented Sept. 5, 1916.

Application filed August 23, 1915. Serial No. 46,994.

To all whom it may concern:

Be it known that we, REYNOLD JANNEY and JOHN J. CRAIN, citizens of the United States, residing at New York and Wallingford, respectively, in the counties of New York and New Haven, respectively, and States of New York and Connecticut, respectively, have invented certain new and useful Improvements in Driving Mechanism, of which the following is a specification.

This invention relates to driving mechanism, one of the fundamental objects of the invention being to provide efficient means of the kind set forth which can be accurately and readily governed to effect changes or variations in speed of a member driven by said mechanism. Said mechanism may be combined with various kinds of devices, and although it is of particular utility for actuating a member which has a back and forth movement by which we mean either what is known as a reciprocation or an oscillation, it is otherwise useful. For example, said mechanism might be employed for moving a part in one direction or for a portion of such movement, while independent means or even gravity might be utilized to effect the return movement of such part, or the reverse might be the case.

In the drawings accompanying and forming part of the present specification we have illustrated in full one of the many different forms of embodiment of the invention which will be set forth in detail in the following description. We do not restrict ourselves to this particular showing; we can depart therefrom in several respects within the scope of the invention defined by the claims following said description.

As we have already noted the driving mechanism is susceptible of general use. In said drawings, however, it is shown combined with a metal working machine, which although represented as a planer, need not necessarily be so as the said mechanism can reciprocate or otherwise operate the slide or equivalent carrier of some other kind of machine.

Referring to said drawings: Figure 1 is a top plan view partly in section of a planer provided with driving mechanism involv-

ing the invention. Fig. 2 is a longitudinal, vertical sectional view showing the reciprocating table and part of the operating gearing. Fig. 3 is a view of a portion of a planer and the driving mechanism, the latter being in top plan view and the planer being partly in plan and partly in horizontal section. Fig. 4 is a detail view of a part of the bed, the table thereon, the dogs, the oscillatory lever and certain other parts. Fig. 5 is a front elevation of the intermediate portion of the planer and the driving mechanism, the motor associated with the driving mechanism, being omitted. Fig. 6 is an elevation as seen from the right in Fig. 5, the upper portion and the right side of the planer being removed. Fig. 7 is a view of the driving mechanism, partly in section, the view being from the inside or opposite to that of Fig. 5. Fig. 8 is a top plan view of said driving mechanism, and, Fig. 9 a view of the same as seen from the right in Fig. 8, the gear casing being partly in section. Fig. 10 is a transverse section through the planer showing part of the gear mechanism for reciprocating the table thereof. Fig. 11 is a detail view in sectional elevation of the driving mechanism at the motor end thereof or what is shown as being the right end in Figs. 1 and 3.

Like characters refer to like parts throughout the several views, which it will be observed are on different scales.

We have shown our driving mechanism as combined with a planer. The planer shown comprises a bed 2 having ways for supporting the work table 3 which is reciprocatory in a straight path. This table or slide 3 presents as may be inferred merely one of many kinds of members which can be advantageously operated by our driving mechanism. On the under side of the table 3 is a longitudinally extending rack 4 (Figs. 2 and 10) in mesh with the pinion 5 which in turn meshes with the spur gear 6, the shafts 7 and 8 of the respective gears 5 and 6 being suitably supported by the bed or framing 2 of the planer. The shaft 8 extends outwardly beyond the bed 2 and as illustrated has fastened to its outer end, the bevel gear 9 (Figs. 3 and 10) in mesh with the bevel gear 10 fastened to the shaft

11, the framing of the planer being provided with suitable means for supporting the shaft 11 and for also incasing the gears 9 and 10.

5 We have described one convenient means by which the table 3 can be operated. It will be clear that when the shaft 11 is turned one way the table 3 through the intervening described parts will be moved in a predetermined direction while on reverse movement of said shaft 11, opposite movement of the table will result through said intermediate parts. In the present case the shaft 11 or equivalent member is automatically oppositely rotated so as to effect reciprocations of the table 3.

We prefer to employ as part of the driving mechanism, what is known as a "hydraulic variable speed gear." Such a device is 20 shown in the drawings and generally speaking is practically a duplicate of that set forth in Letters Patent No. 924,787 granted to Reynold Janney, June 15, 1909. As the invention does not reside *per se* in a hydraulic variable speed gear, we will not describe in detail that represented. It is deemed desirable, however, to briefly set forth the organization of such a device which comprises a driving shaft or as it is 25 some times known "A-shaft" as 12, and a driven shaft, or as it is some times called "B-shaft" as 13. Although the part 12 has been considered as a driving shaft it in turn is driven by power preferably continuously, 30 the electric motor 14 (Figs. 1 and 3) being shown for this purpose, the armature shaft of the motor being connected with the shaft 12 by gearing such as that denoted in a general way by 15. As represented the driven 35 or B-shaft is connected by a flexible coupling as 17 or otherwise with the shaft 11. It will, therefore, be obvious that the speed of the shaft 11 and the direction of movement thereof will conform to those of the driven 40 or B-shaft 13. In the casing of the hydraulic variable speed gear is mechanism by which through the aid of suitable means the shaft 13 or analogous element can be driven either forward or backward at different 45 speeds. As a part of the hydraulic variable speed gear is a controller which may take the form of a shaft, and a regulator which may consist of what is known as a "tilting box." This regulator or tilting box has a 50 neutral position, and when occupying the same the shaft 13 will be at rest or stationary. If said regulator or tilting box be moved in one direction from said neutral position, the shaft 13 will be driven, for instance forward, while if the tilting box be moved in the opposite direction from said neutral position, the shaft 13 will be turned oppositely, the velocity of the shaft 13 depending upon the position of said tilting 55 box. It will be evident that as the tilting

box, merely one of several types of regulators suitable for the purpose, leaves its neutral position, the speed of the shaft 13 will be progressively increased. The controller is denoted by 18 and is connected 70 with the tilting box or regulator 19. The lower end of the control shaft 18 is connected with the tilting box 19, being threaded between its ends to fit the threads of the nut 20, said nut being made in the form of a 75 bevel gear, so that it can be turned as will hereinafter appear. The nut is immovable in the direction of its axis of movement. It will, therefore, be clear that if the control shaft 18 be turned with respect to the bevel gear or nut 20, said control shaft will be moved endwise, its endwise movement depending upon the direction in which said control shaft is turned, by virtue of which said control shaft by its said endwise movement can effect a change in position of the tilting box 19 to move it from its neutral position in either direction as already stated. The mounting and action of the control shaft 18 are exactly like what is 80 shown in Letters Patent 1,108,443 issued August 25, 1914 to Reynold Janney. In this particular patent is shown what is known as a "follow-up" motion, and this follow-up motion we use in the present case, 85 but, however, for a different purpose.

In conjunction with the control shaft 18 or its equivalent we provide means for limiting the motion thereof in opposite directions from the neutral, it being evident that the shaft is in its neutral position when the tilting box is in its neutral position. The means shown whereby this function may be secured answers satisfactorily and will now be described. Fulcrumed at one end for instance to parallel links as 21 mounted for swinging movement upon a suitable bearing at the outer end of the hydraulic variable speed gear, is a lever 22 (Figs. 3 to 8 inclusive). Said lever has between its ends the loop 23 in which is pivoted the block 24 connected to the upper end of the control shaft 18 so that as the control shaft 18 moves upward from its neutral position or downward therefrom, the lever 22 is respectively swung up and down. The extent of movement of said lever governs the speed of the shaft 13 and through the intermediate described parts that of the 100 table 3. It will, of course, be obvious that the table can be driven slowly in one direction and quickly in the other and vice versa. The governing lever 22 has at its inner end the guide-eye 25 to receive the rod 26 equipped with adjustable stops 27 and 28, hereinafter more particularly described. The two stops are shown at the limits of their outer adjustments. By moving them in toward the eye 25, the motion of the lever 22 will be decreased so as to correspondingly 105 110 115 120 125 130

decrease the velocity of the shaft 13. The stop 27 will govern the speed of the table 3 in one direction while the stop 28 will govern the speed of the table in the opposite direction. The stops 27 and 28 consist of elongated sleeves slideable on the stationary rod 26, each being provided with a thumbscrew 29 to hold the same in an adjusted position, the thumbscrews as will be apparent, being adapted to engage the said rod. Each of the stops also has a wheel-like or annular manipulating portion 30 which can be grasped to facilitate its adjustment longitudinally of the rod. The rod is connected to and rises from a movably mounted member as will hereinafter appear. The lever 22 is automatically oscillated by means coöperative with the table 3, owing to which said table can be automatically reversed, and suitable means for this purpose will be hereinafter set forth.

Above the A-shaft 12 is an auxiliary shaft 31 (Fig. 7 for example) which is driven continuously in some suitable manner by said A-shaft, sprocket gearing denoted in a general way by 32 being shown for this purpose. Loose on this shaft and housed in the casing 33 are inwardly facing bevel gears 34 and 35, the clutch member 36 being coöperative with the two gears 34 and 35 and being adapted to alternately frictionally clutch said gears to the continuously rotative shaft 31. This clutch member 36 is splined or feathered to the shaft 31 for rotation therewith and longitudinal movement thereof, its opposite cone ends being adapted to alternately engage the walls of the conical cavities 37 in the said gears 34 and 35. In Fig. 7 the clutch member 36 is shown as occupying its neutral position, the same applying to the control shaft 18 and governing lever 22, the consequence being that the driven shaft 13 will be at rest. The two bevel gears 34 and 35 mesh with the bevel gear 38 (Figs. 8 and 9) rigid with the bevel gear 39, the latter in turn meshing with the bevel gear 18' which is splined to the control shaft 18. It will, therefore, be clear that on the turning of said gear 18' said control shaft owing to its threaded connection with the gear or nut 20 assumed to be stationary at this time, said shaft 18 will be moved endwise, its direction of movement depending upon the direction in which said bevel gear 18' is turned.

The clutch member 36 in the present case is movable back and forth on the auxiliary shaft 31 by the shipper member 40 shown as being of oscillatory form and pivoted between its ends for swinging movement. To the lower branch of the shipper member 40 is jointed the rod 41 as shown best in Fig. 7 (see also Figs. 1, 3 and 5). This rod 41 is also jointed to the oscillatory member 42 pivoted on the framing of the planer and to

which in turn the rod 43 is connected, said rod in turn having a connection with the lever or rocker 44 mounted on the bed 2 and shifted in alternate directions by dogs as 45 and 46. These dogs and lever 44 and connecting rod 43 are common in planers and therefore, require no extended description, the dogs as understood to those conversant in the art, being adjustable longitudinally of the bed and being adapted to alternately swing the rocker 44 in opposite directions. The lever or rocker 44 also has a handle 47 by which it can be manipulated to move it to neutral position and thus prevent its operation by said dogs as usual in the art. When the rocker 47 is thus manually operated, it moves through the intermediate described parts the clutch member 36 to its intermediate or neutral position as shown in Fig. 7. During planing or equivalent operation, however, the rocker 44 is rocked alternately in opposite directions by said dogs.

It will be assumed that the A or primary shaft 12 is in action and that the clutch member 36 and controlling shaft 18 and regulator 19 are in their neutral positions. In this event the shaft 13 and hence the table or carriage 3 will be at rest. To start the bed 3 the rocker or lever 44 will be manipulated so as to throw through the intermediate described parts the clutch member 36 into engagement with one or the other of the bevel gears 34 and 35. It will be assumed that the clutch member 36 is moved into engaging relation with the bevel gear 34, and that said bevel gear is utilized to effect through the described connections the movement of the table 3 in a forward direction. As soon as the clutch member 36 is engaged with said bevel gear 34, the latter will be rotated to effect through the parts described including the bevel gear 18' the elevation of the control shaft 18 and lever 22, this motion continuing until the lever strikes the upper stop 28 at which point further motion of the lever and control shaft will be practically arrested. As the control shaft 18 is swung up the tilting box 19 is moved upward from its neutral position to cause the movement of the shaft 13 at the requisite speed and said shaft 13, owing to its described connections with the table 3, will advance said table until the dog 45 strikes the lever 44 and swings the same over the slide 120. The slide 120 concludes its advancing movement, the clutch member through the primary influence of the dog 45 being engaged with the gear 35. As soon as the clutch member 36 is clutched to the gear 35 the control shaft 18 and therefore lever 22 are lowered until the lever strikes the stop 27, the lowering of the shaft 18 from its upper extreme position to its lower extreme position effecting a reversal of movement of the tilting box 19 and 130.

therefore a reversal in motion of the shaft 13, by virtue of which return movement of the slide 3 is effected, continuing until the dog 46 strikes the lever 44 and swings said lever over so as to cause the clutch member 36 through the described parts to again engage the gear 34 at which point the motion of the table 3 is reversed or said table is caused to advance, these operations continuing in sequence as long as the lever 44 is positioned for alternate operation by the dogs 45 and 46.

The rod 26 is rigidly connected with and rises from the arm 64 which it will be remembered, is connected with the shipper member 40. It will be noted that we have mentioned the fact that the motion of the lever 22 is virtually arrested in alternation by the stops 27 and 28. This lever when it strikes either stop has a slight further movement. On this further movement it will raise the rod 26 if the stop 28 is struck, while if the lever engages the stop 27 the rod will be lowered during this final and almost imperceptible movement of the lever 22.

As a matter of fact the motion of the lever is practically stopped when it strikes either of the stops. There will be a small amount of motion and this is utilized to disengage the clutch member 36 from the gears 34 or 35 which it may engage. For instance on the final part of the movement of the lever 22 after the latter has struck the stop 28, the rod 26 will be raised, thus raising the arm 64 and through the shipper 40 disengaging the clutch member 36 from the bevel gear 34. On downward movement of the lever 22 the arm 64 as will be inferred, is moved downward through the action of the rod 26 so as to cause the clutch member 36 to be disengaged from the bevel gear 35. When the clutch member is engaged with the bevel gear which for the time being it cooperates with further motion of such bevel gear and therefore of the bevel gear 38 and parts actuated by the latter will be arrested.

Fastened in some suitable manner to the driven or secondary shaft 13 from the hydraulic variable speed gear, is the pinion 50 in mesh with the spur gear 51. This spur gear 51 is fastened to the section 52 of a divided shaft, the section 53 of said divided shaft having a bevel pinion 54 (see Fig. 11) in mesh with the gear or nut 20 with which it will be remembered the control shaft 18 has a threaded connection as shown for example in Figs. 7, 8 and 11. As will be understood the shaft sections 52 and 53 are coaxial and to them are connected clutch members 55 and 56 of friction type, the clutch section 55 being rotative with the shaft section 52 and the clutch section 56 being rotative with and movable longitudinally of the shaft section 53. Surrounding the clutch section 56 is a split band 57 to

which the parallel links 58 are connected (Figs. 7 and 8), these links being connected by the pin 59 which is in turn connected with a crank arm 60 fastened to the shaft 61 mounted on the bracket 62 sustained by the hydraulic variable speed gear. To the shaft 61 is fastened a crank arm 63 to which the link 64' is pivoted, said link being jointed to the arm 64 rigid with the shipper member 40 already described, the parts being so positioned that when the clutch member 36 is moved from either direction toward its neutral position, the clutch section or member 56 will be caused to engage the clutch section or member 55 so that the tilting box or regulator 19 can be moved to its neutral position. It will be clear that when the shaft 13 is in motion the gears 50 and 51 will be rotated so as to rotate the shaft section 52, and if the clutch sections 55 and 56 be not in engagement the shaft section 53 will not be rotated. It will, therefore, be evident that when the lever 44 is manipulated to throw it to its mid position where it can be operated by either of the dogs 45 or 46, the clutch member 36 will be moved to its neutral position and at the same time through the described parts, the clutch member 56 will be caused to engage the clutch member 55, so that the shaft section 53 can in the manner already set forth be rotated to rotate the bevel pinion 54 and therefore the nut or bevel gear 20. When the nut is turned the control shaft will be returned to its neutral position, and as said control shaft is returned to its neutral position, the tilting box through its connection with said control shaft is also returned to its neutral position, and when the latter occurs rotation of the shaft 13 is stopped.

To the bevel gear 34 is connected a suitable manipulating hand wheel 65 which presents a convenient means for moving primarily at the will of the operator, the carriage or table 3 to a predetermined position. It will be assumed that the clutch member 36 has been moved to its neutral position and that the control shaft 18 and regulator 19 are in corresponding relations and that it is desired to effect manually the adjustment of the slide or table 3. In this event the hand wheel 65 is turned to raise or lower through the intermediate parts the regulator 22 and thereby in the manner described effect the turning of the driven or secondary shaft 13 and therefore, the desired movement of the slide or table 3. As soon as the table or slide is in the adjusted position the regulator or tilting box 19 will be moved to its initial or neutral position through the agency of the clutched shaft sections 52 and 53 and bevel gear 54 acting in the manner already described. It will be understood that when the hand wheel 65 is turned to effect the movement of the tilting box 19

from the neutral there is another train of devices tending to return said tilting box to neutral and to effect the movement of the slide, carriage or table 3 to an adjusted position it will be necessary to turn the hand wheel 65 faster than the opposing parts act against the tilting box, these opposing parts presenting what is known as a follow-up motion. With the clutch member 36 in the neutral and the adjustment being attained through the operation of the hand wheel 65 or analogous part, the tilting box 19 is returned to its neutral position practically instantly after the hand wheel 65 is freed by the operator.

This train of devices to which we have referred is what is known in this art as a follow-up mechanism, and in the construction shown comprises the gears 50 and 51, the shaft sections 52 and 53 (when clutched together) bevel gear 54, bevel gear or nut 20 and control shaft 18 which it will be remembered is connected with the tilting box.

What we claim is:

1. The combination of a reciprocatory member, a hydraulic variable speed gear having a regulator and also having driving and driven members, the driven member being operatively connected with said reciprocatory member to operate the same and the regulator being shiftable to effect reversals in movement and variations in speed of the driven member, oppositely rotative members, means governed by the reciprocatory member, for alternately connecting said oppositely rotative members with a source of power, a controller for operating said regulator, means actuated by said oppositely rotative members, for causing opposite motions of the controller, and means settable at will, for governing the amount of opposite motions of the controller.

2. The combination of a reciprocatory member, a hydraulic variable speed gear having a regulator and also having driving and driven members, the driven member being operatively connected with said reciprocatory member to operate the same and the regulator being shiftable to effect reversals in movement of the driven member, oppositely rotative members, means governed by the reciprocatory member, for alternately connecting said oppositely rotative members with a source of power, a controller for operating said regulator, means actuated by said oppositely rotative members, for causing opposite motions of the controller, and means for limiting said opposite motions of the controller.

3. The combination of a reciprocatory member, a hydraulic variable speed gear having a regulator and also having driving and driven members, the driven member being operatively connected with said reciprocatory member to operate the same,

and the regulator being shiftable to effect reversals in movement of the driven member, oppositely rotative members, means for automatically alternately connecting said oppositely rotative members with said driving member, a controller for operating said regulator, and means actuated by said oppositely rotative members, for causing opposite motions of the controller.

4. The combination of a reciprocatory member, a hydraulic variable speed gear having a regulator and also having driving and driven members, the driven member being operatively connected with said reciprocatory member to operate the same and the regulator being shiftable to effect reversals in movement of the driven member, oppositely rotative members, means for alternately connecting said oppositely rotative members with a source of power, a controller for operating said regulator, and means actuated by said oppositely rotative members, for causing opposite motions of the controller.

5. The combination of a reciprocatory member, a hydraulic variable speed gear having a regulator and also having driving and driven members, the driven member being operatively connected with said reciprocatory member to operate the same and the regulator being shiftable to effect reversals in movement and variations in speed of the driven member, oppositely rotative members, means governed by the reciprocatory member, for alternately connecting said oppositely rotative members with a source of power, a controller for operating said regulator, means actuated by said oppositely rotative members, for causing opposite motions of the controller, and independently adjustable means, for governing the amount of opposite motions of the controller.

6. The combination of a reciprocatory member, a hydraulic variable speed gear having a regulator and also having driving and driven members, the driven member being operatively connected with said reciprocatory member to operate the same and the regulator being shiftable to effect reversals in movement and variations in speed of the driven member, a rotary shaft, bevel gears loose on the shaft, a bevel gear in mesh with the other bevel gears, a clutch member between the first mentioned bevel gears, means governed by the reciprocatory member, for operating said clutch member to alternately clutch the first mentioned bevel gears to said shaft, a controller for operating said regulator, means actuated by said last mentioned bevel gear, for causing opposite motions of the controller, and means for governing the amount of opposite motions of the controller.

7. The combination of a reciprocatory

member, a hydraulic variable speed gear having a regulator and also having driving and driven members, the driven member being operatively connected with said reciprocatory member to operate the same and the regulator being shiftable to effect reversals in movement of the driven member, a shaft operatively connected with and rotative by said driven member, bevel gears loose on said shaft, a clutch member, means governed by the reciprocatory member, for operating the clutch member to effect clutching of said gears alternately to said shaft, a bevel gear in mesh with the other bevel gears, a controller for operating said regulator, and means actuated by said last mentioned bevel gear, for causing opposite motions of the controller.

8. The combination of a reciprocatory member, a hydraulic variable speed gear having a regulator and also having driving and driven members, the driven member being operatively connected with said reciprocatory member to operate the same and the regulator being shiftable to effect reversals in movement of the driven member, oppositely rotative members, means governed by the reciprocatory member for alternately connecting said oppositely rotative members with a source of power, and mechanism actuated by said oppositely rotative members for causing opposite motions of the controller and for alternately disconnecting said oppositely rotative members from the source of power approximately at the conclusion of said opposite motions.

9. The combination of a reciprocatory member, a hydraulic variable speed gear having a regulator and also having driving and driven members, the driven member being operatively connected to said reciprocatory member to operate the same and the regulator being shiftable to effect reversals in movement of the driven member, oppositely rotative members, a clutch member, means governed by the reciprocatory member for operating said clutch member to alternately connect said oppositely rotative members with a source of power, a controller for operating said regulator, means actuated by said oppositely rotative members, for causing opposite motions of the controller, and means for disengaging the clutch member from said oppositely rotative members approximately at the conclusion of the opposite movements of the controller.

10. The combination of a reciprocatory member, a hydraulic variable speed gear having a regulator and also having driving and driven members, the driven member being operatively connected with said reciprocatory member to operate the same and the regulator being shiftable to effect reversals in movement and variations in speed of the driven member, oppositely rotative

members, a clutch member, means governed by the reciprocatory member for operating the clutch member to cause said oppositely rotative members to be connected with a source of power, a controller for operating said regulator, means actuated by said oppositely rotative members for causing opposite motions of the controller, and mechanism for varying the amount of opposite motions of the controller and for disconnecting the clutch member with that one of the opposite rotative members with which it is in engagement, at approximately the conclusion of each motion of the controller.

11. The combination of a reciprocatory member, a hydraulic variable speed gear having a regulator, and also having driving and driven members, the driven member being operatively connected with said reciprocatory member to operate the same and the regulator being shiftable to effect reversals in movement and variations in speed of the driven member, oppositely rotative members, means governed by the reciprocatory member for alternately connecting said oppositely rotative members with a source of power, a control shaft operatively connected with the regulator, a power transferring member co-operative with and alternately rotative in opposite directions by said oppositely rotative member, said power transferring member having a feed connection with said control shaft to effect opposite movements of the control shaft in a longitudinal direction, a lever having a connection with said control shaft and movable thereby in opposite directions, and stops adjustable at will for governing the opposite movements of said lever.

12. The combination of a reciprocatory member, a hydraulic variable speed gear having a regulator and also having driving and driven members, the driven member being operatively connected with said reciprocatory member to operate the same and the regulator being shiftable to effect reversals in movement and variations in speed of the driven member, a shaft operatively connected with said driving member, bevel gears loose on said shaft, and facing each other, a clutch member splined to the shaft for sliding movement thereon, means governed by the reciprocatory member for operating said clutch member to cause the same to alternately clutch said gears to said shaft, and including a clutch member shifting device, a bevel gear in mesh with said other bevel gears and operatively rotative in alternation thereby, a controller oppositely movable by said last mentioned bevel gear, a rod provided with adjustable stops, and operatively connected with said clutch member shifting device, and a member connected with the controller oppositely movable thereby and adapted to engage said stops approximately 130

at the conclusion of opposite motions of the controller and to also operate said rod in an endwise direction.

13. The combination of a reciprocatory member, a hydraulic variable speed gear having a regulator and also having driving and driven members, a shaft operatively connected with the driving member, bevel gears loose on the shaft and operatively connected with each other, a clutch member splined to the shaft for sliding movement thereon, a shifting device connected with the clutch member, means governed by the reciprocatory member for operating said shifting device to cause the clutch member to alternately clutch said gears to said shaft, a bevel gear in mesh with both of the other bevel gears, a controller oppositely movable by said last mentioned gear on alternate movements of the latter, a lever connected with said controller, and a rod operatively connected with said shifting device, provided with adjustable stops alternately engageable by said lever.
14. The combination of a reciprocatory member, a hydraulic variable speed gear having a regulator and also having driving and driven members, the driven member being operatively connected with said reciprocatory member to operate the same and the regulator being shiftable to effect reversals in movement of the driven member, oppositely rotative members, means governed by the reciprocatory member for alternately connecting said oppositely rotative members with a source of power, and means actuated by said alternately rotative members, for causing opposite movements of the regulator.
15. The combination of a reciprocatory member, a hydraulic variable speed gear having a regulator and also having driving and driven members, the driven member being operatively connected with said reciprocatory member to operate the same, and the regulator being shiftable in opposite directions to effect reversals in movement of the driven member, oppositely rotative members, means governed by the reciprocatory member, for alternately connecting said oppositely rotative members with a source of power, means actuated by said oppositely rotative members, for causing opposite movements of the regulator, and means settable at will for governing the amount of opposite motions of the regulator.

16. The combination of a hydraulic variable speed gear having a regulator and also having driving and driven members, the regulator being shiftable to opposite sides of a neutral position to effect reversals in movement of the driven member, oppositely rotative members, automatically operative means for alternately connecting said oppositely rotative members with a source of

power, and means actuated by said oppositely rotative members, for causing movements of the regulator at opposite sides of its neutral position.

17. The combination of a hydraulic variable speed gear having a regulator and also having driving and driven members, the regulator being shiftable to opposite sides of a neutral position to effect reversals in movement of the driven member and movable to different points to regulate the speed of said driven member, oppositely rotative members, means for alternately automatically connecting said oppositely rotative members with a source of power, and means settable at will, for governing the amount of opposite motions of the regulator.

18. The combination of a hydraulic variable speed gear having a regulator and also having driving and driven members, the regulator being shiftable to effect reversals in movement of the driven member, oppositely rotative members, automatically operative means for alternately connecting said oppositely rotative members with a source of power, and mechanism actuated by said oppositely rotative members for effecting opposite movements of the regulator and for also disconnecting said oppositely rotative members from said source of power approximately at the conclusion of the opposite movements of the regulator.

19. The combination of a hydraulic variable speed gear having a regulator and also having driving and driven members, the regulator being shiftable to opposite sides of a neutral position to effect reversals in movement of the driven member, a shaft operatively connected with said driving member, bevel gears facing each other loose on said shaft, a clutch member, a shifting device for the clutch member, a bevel gear in mesh with the other bevel gear, mechanism acting against said device to cause said clutch member to alternately engage said first mentioned bevel gears, and means for disengaging the clutch member from said first mentioned bevel gears approximately at the conclusion of the movements of the regulator.

20. The combination of a hydraulic variable speed gear having a regulator and also having driving and driven members, the regulator being shiftable oppositely from a neutral position to effect reversals in movement and variations in speed of the driven member, a shaft operatively connected with the driving member, bevel gears loose on the shaft and facing each other, a clutch member between the bevel gears, for clutching the same to the shaft, a shifting device for the clutch member, automatic means acting against the shifting device to cause the same to move the clutch member alternately into engagement with said bevel

- gears, a bevel gear in mesh with the other bevel gears, a control shaft endwise movable by said last mentioned bevel gear, a lever connected with said control shaft, and a rod provided with adjustable stops alternately engageable by said lever and operatively connected with said clutch member shifting device.
21. The combination of a hydraulic variable speed gear having a regulator and driving and driven members, the regulator being shiftable to opposite sides of a neutral position to effect opposite movements of the driven member, and mechanism for automatically connecting the regulator with a source of power to effect opposite movements of the regulator and for disconnecting the regulator with the source of power approximately at the conclusion of the opposite movements.
22. The combination of a reciprocatory member, a hydraulic variable speed gear having a regulator and also having driving and driven members, the driven member being operatively connected with said reciprocatory member to operate the same and the regulator being shiftable to effect reversals in movement of the driven member, oppositely rotative members, means governed by the reciprocatory member for alternately connecting said oppositely rotative members with a source of power, a controller for operating said regulator, means actuated by said oppositely rotative members for causing opposite motions of the controller, and operative connections involving a clutch, between the driven member and the controller.
23. The combination of a hydraulic variable speed gear having a regulator and also having driving and driven members, the regulator being shiftable to opposite sides of a neutral position to effect reversals in movement of the driven member, oppositely rotative gears, a clutch for alternately connecting said operatively rotative gears with a source of power, gear means operative in alternation by said oppositely rotative gears for effecting opposite movements of the regulator, and operative connections between the driven member and said gear means, including a clutch.
24. The combination of a hydraulic variable speed gear having a regulator and also having driving and driven members, the regulator being shiftable to opposite sides of a neutral position to effect reversals in movement of the driven member, bevel gears facing each other, a shaft operatively connected with said driving member and upon which said bevel gears are mounted, a clutch member splined to the shaft for sliding movement thereon, a bevel gear in mesh with the other bevel gears and operatively connected with the regulator, and connections between the driven member and the last mentioned bevel gear, involving a clutch.

In testimony whereof we affix our signatures in presence of two witnesses.

REYNOLD JANNEY.
JOHN J. CRAIN.
